UNITED STATES PATENT OFFICE.

CHRISTER PETER SANDBERG, OF LONDON, ENGLAND.

BASE-PLATE FOR RAILWAY OR TRAMWAY SLEEPERS.

1,178,351.

Specification of Letters Patent.

Patented Apr. 4, 1916.

Application filed May 24, 1915. Serial No. 30,177.

To all whom it may concern:

Be it known that I, CHRISTER PETER SANDBERG, a subject of the King of Great Britain, residing in London, England, have invented a certain new and useful Improved Base-Plate for Railway or Tramway Sleepers, of which the following is a specification.

In order to distribute the load on a railway or tramway sleeper carrying a flange rail a base plate has been used on which the rail rests. Such plate has always been held to the sleeper by bolts, screws or other separate pieces which not only require periodical attention but involve additional cost and labor. It has also been proposed with metal sleepers to employ a base plate merely laid upon the sleeper between metal lugs and held in position by said lugs from both endwise and sidewise movement. The lugs in such an arrangement have also been used for gripping the flange of a flange rail.

The present invention provides a base plate for steel sleepers of the kind in which either a flange rail or a bull head rail is held by a key or wedge between a part of the rail, preferably the web, and a tongue turned up from the metal of the sleeper.

It consists essentially in the combination with a metal sleeper of the type mentioned of a base plate to distribute the load upon the sleeper adapted to be held in position by the relative relations of the rail, the base plate, and the sleeper.

The invention will be more particularly described with reference to the accompanying drawings which show three applications of the invention.

Figure 1 is a view showing the invention as applied to one form of sleeper. Fig. 2 is a plan of same. Fig. 3 is a view showing the invention applied to another type of rail and sleeper. Fig. 4 is a plan of same. Fig. 5 is a view showing another application of the invention. Fig. 6 is a plan of same.

In Figs. 1 and 2 the invention is shown as applied to a sleeper A adapted to support a flange rail B and having clips C to clip or hold the flanges b of the rail, a wedge or key D being driven under one clip to hold the rail tightly in position. The base plate E as applied to such a sleeper is simply laid in position on the sleeper between the clips C and is formed at one or both sides with shoulders F

adapted to embrace one or both of the clips C for the purpose of preventing any movement of the plate E longitudinally of the rail. The clips C have at their lower ends a spacing which is greater than the width of the plate E whereby said plate may be initially adjusted to a position most favorable to its effective grip of the rail base or flange. The plate E may also if desired be provided with a shallow groove G adapted to receive the flange of the rail and to prevent any movement of the plate longitudinally of the sleeper. The plate E is held in position by the weight or pressure of the rail B upon it, which is increased by the pressure exerted by the wedge or key D through the flange b of the rail. Or, as shown, the wedge may press directly upon the plate E as well as upon the flange b.

In Figs. 3 and 4 the plate E' is shown as applied to a sleeper A in which the tongues or clips C' form the jaws of a chair adapted to hold a bull head rail B' in the ordinary manner by means of a wedge or key D' adapted to engage the web of the rail. The base plate E' is applied in a manner similar to that shown in Figs. 1 and 2 being merely laid upon the sleeper between the jaws C', whose spacing at their lower ends is greater than the width of the plate E'. In this arrangement the plate E' is shown with shoulders F' formed only at one side to embrace one of the jaws C'. The shallow groove G' to receive the rail B' may be given an inclination as shown in this arrangement to give any required cant or inclination to the rail. The plate is held in position exactly as described with reference to Figs. 1 and 2.

In Figs. 5 and 6 the plate E'' is shown as applied to another type of sleeper having jaws C'' adapted to form a chair to receive a flange rail B. The plate E'' is applied in the same manner as above described and is very similar in construction to that shown in Figs 1 and 2; the groove G'' is shown inclined to give a cant to the rail B and the plate E'' is held down by the combined weight of the rail and the pressure exerted through it of the key or wedge D'' and the distance piece H. Such a base plate is particularly applicable when two or more tongues forming clamps or jaws are turned up from the same slot in the sleeper as described in my pending application, Serial 110

No. 28,806. It is shown as applied to such a sleeper in Figs. 3, 4, 5 and 6 of the drawings.

Having thus described my invention and the best means I know of carrying the same into practical effect, I claim:—

1. The combination with a metal sleeper having spaced jaws which provide a rail chair, of a base plate interposed between said jaws and of less width than the space between the jaws at their lower ends whereby an initial adjustment of the position of said plate may be made, said plate serving to distribute the load upon the sleeper and having means for coöperation with one of the jaws and with the rail whereby it will be positively held in position.

2. The combination with a metal sleeper having spaced jaws which provide a rail chair, of a base plate interposed between said jaws and of less width than the space between the jaws at their lower ends whereby an initial adjustment of the position of said plate may be made, said plate serving to distribute the load upon the sleeper and being shaped for coöperation with one of said jaws and with said rail whereby it is positively held in position.

3. The combination with a metal sleeper having spaced jaws which provide a rail chair, of a base plate interposed between said jaws and of less width than the space between the jaws at their lower ends whereby an initial adjustment of the position of said plate may be made, said plate serving to distribute the load upon the sleeper and having a groove to receive the base of the rail whereby the plate will be positively held by the rail against movement longitudinally of the sleeper.

4. The combination with a metal sleeper having spaced jaws which provide a rail chair, of a base plate interposed between said jaws and of less width than the space between the jaws at their lower ends whereby an initial adjustment of the position of said plate may be made, said plate serving to distribute the load upon the sleeper and having an inclined groove to receive the base of the rail whereby the rail will have a certain cant and the plate will be positively held by the rail against movement longitudinally of the sleeper.

5. The combination with a metal sleeper having a projection rigid therewith, of a base plate imposed upon said sleeper and adapted to be initially adjusted to a favorable position, said plate serving to distribute the load upon the sleeper and having shoulders to coöperate with said projection in positively preventing displacement of the plate longitudinally of the rail and having also a groove to receive the base of the rail whereby the plate will be held by the rail against displacement longitudinally of the sleeper.

6. The combination with a metal sleeper, of a base plate loosely imposed thereon and adapted to be initially adjusted to a suitable position, said plate having means integral therewith for coöperation with the sleeper and with the rail to positively prevent its movement in any direction.

In testimony whereof I have signed my name to this specification in the presence of two subscribing witnesses.

CHRISTER PETER SANDBERG.
